UNITED STATES PATENT OFFICE.

CHARLES C. DE LAPPE AND CHARLES H. SMITH, OF BOSTON, MASSACHUSETTS.

GARBAGE-CREMATOR.

1,219,631.

Specification of Letters Patent. Patented Mar. 20, 1917.

Application filed April 28, 1916. Serial No. 94,244.

To all whom it may concern:

Be it known that we, CHARLES C. DE LAPPE and CHARLES H. SMITH, citizens of the United States, residing at Boston, in the county of Suffolk and State of Massachusetts, have invented new and useful Improvements in Garbage-Cremators, of which the following is a specification.

The object of the present invention is to provide an improved cremator suitable for domestic use for cremating garbage.

One of the features of the invention is the construction whereby the lid may be effectually sealed, with the aid of water, to prevent the escape of gases from the device into the room where it is being used.

The cremator is adapted to be placed upon a household coal-burning range and is adapted to utilize the heat from the coal burning in such range, but it is nevertheless provided with gas burners arranged to produce the heat necessary for cremation when, for example, there is no coal undergoing combustion in the range.

Of the accompanying drawings, which illustrate one form in which the present invention may be embodied:

Figure 1 represents a top plan view of our improved cremator, a portion of the lid being broken away to disclose the interior.

Fig. 2 represents a vertical section including the cremator and a portion of a coal-burning range, the cremator being arranged in coöperative relation to such range.

The same reference characters indicate the same parts wherever they occur.

The container for the garbage or other refuse is in the form of a cage and is indicated at 10. The term "cage" is used to imply that the container has openings for the escape of gases, regardless of whether such openings are perforations or the spaces between the wires of a fabricated container. In the present instance the cage is made of sheet metal and has perforations 11 for the escape of the gases. The bottom 12 of the cage has a struck-up portion 13 adapted to expedite cremation and the escape of gases from the refuse.

The cage is adapted to set into an annular holder 14, and it has an external shoulder 15 adapted to rest upon an internal ledge 16 of the holder. The holder is adapted to rest upon the top 17 of a range, and it has a depending annular flange portion 18

adapted to set into one of the usual pot-holes in the top of the range, Fig. 2 showing the flange portion 18 in one of such pot-holes.

Three coöperative walls of the fire-pot are indicated at 19, 20 and 21, and the coal for combustion is indicated at 22. Although the drawings do not illustrate the outlet through which the products of combustion pass to enter the usual flue, it may be assumed that such products flow in the direction indicated by an arrow in Fig. 2. An air slide is indicated at 23. Assuming that the coal 22 is undergoing combustion and that the cremator is installed as shown and has refuse in the cage 10, the heat from the coal will evaporate the moisture from such refuse and carry such moisture with it to the flue (not shown). When substantially all the moisture has been taken from the refuse in this way, the latter may be dumped upon the coal 22 and reduced to ashes.

The cremator is provided with a lid which comprises a depending annular flange portion 24 and a concave crown 25. This lid coacts with the holder 14 to prevent the escape of gases from the cremator to the atmosphere, excepting the escape to the flue hereinbefore mentioned. The holder 14 is provided with an annular channel 26 adapted to receive the flange 24 and adapted to hold water 27 to provide a lute. The lid is provided with a handle 28, and the latter is fastened to the crown 25 in the concavity of the latter by rivets 29. The concavity of the crown may be filled with water. This would prevent extreme heating of the handle, and would prevent the escape of gases through the rivet holes in case the latter were not completely closed by the rivets. The vapor from the garbage, on striking the water-cooled lid, condenses and runs to the center before dropping. After the cremator has been installed and is ready to receive the water to seal the lid, such water may be poured into the concavity of the crown, and whatever water overflows the rim of the crown will lodge in the channel 26.

We have provided the cremator with gas-burning apparatus adapted to cause cremation without burning fuel in the fire-pot of the range. The holder 14, which is preferably made of cast iron, is provided with a gas duct 30. This duct, in the present instance, is annular and is formed in the flange portion 18. A mixer for air and gas is in-

dicated at 31 and is screwed into the side of the holder. A duct 32 forms communication between the mixer and the duct 30. The mixer is provided with a cock 33 to which a flexible gas tube may be attached. One or more gas burners 34 may be provided. We have shown three in the present instance. These burners are connected to the annular flange portion 18 and are in communication with the duct 30. The openings for the emission of gas are indicated at 35. The burners are arranged in coöperative relation to the cage 10, the openings 35 facing the cage so that the flames will impinge against the cage and apply the heat to the refuse in the most efficient way. The burners project below the bottom of the cage and have offset extremities 36 extending toward a common center, said extremities having burner openings 35* arranged to direct the flames against the bottom of the cage. These burners may be permanent parts of the cremator, and their presence would not interfere with the use of the device in conjunction with coal or wood that might be burning in the fire-pot of the range.

The cage 10 may be lifted out of the holder 14 without removing the holder from the top of the range. It may be observed that the bottom 12 of the cage is eccentric with relation to the upper portion, holder, and pot-hole of the top 17. The purpose of such eccentricity is to enable the cremator to be turned to an angular position wherein the bulk of the refuse will be more nearly

in the path traversed by the products of combustion from the fire-pot.

A detachable handle is indicated at 37. This handle has a lip 38 adapted to go into an inverted channel 39 formed in the holder 14. The handle has a portion 40 adapted to bear against a substantially upright surface of the holder 14, such as surface 41. When the handle 37 is used to lift the cremator the portion 41 is adapted to keep the cremator in an upright position while the weight of the cremator is sustained by lip 38.

We claim:

1. A garbage cremator comprising a cage, an annular holder therefor, and a lid having a depression adapted to hold water, and having a depending annular flange encircling said depression, said holder having an annular channel adapted to receive said flange and adapted to catch whatever water overflows said depression.

2. A garbage cremator comprising a cage, an annular holder therefor having a duct, said duct having an inlet for combustible gas, one or more gas burners arranged below and sustained by said holder in coöperative relation to said cage, said burners being in communication with said duct, and a lid adapted to coact with said holder to inclose the upper part of said cage.

In testimony whereof we have affixed our signatures.

CHARLES C. DE LAPPE.
CHARLES H. SMITH.
